Primary Examiner — Wendy L Arminio*(74) Attorney, Agent, or Firm* — The Watson IP Group, PLC; Jovan N. Jovanovic(57) **CLAIM**

The ornamental design for a connector, as shown and described.

DESCRIPTION

FIG. 1 of the drawings is a top perspective view of the connector showing my new design;

FIG. 2 of the drawings is a bottom perspective view thereof;

FIG. 3 of the drawings is a front elevational view thereof;

FIG. 4 of the drawings is a back elevational view thereof;

FIG. 5 of the drawings is a first side elevational view thereof;

FIG. 6 of the drawings is a second side elevational view thereof;

FIG. 7 of the drawings is a top plan view thereof; and,

FIG. 8 of the drawings is a bottom plan view thereof.

The broken lines depict portions of the connector that form no part of the claimed design.

1 Claim, 8 Drawing Sheets(56)
